(57) **CLAIM**

The ornamental design for a brewing machine and carafe, as shown and described.

DESCRIPTION

FIG. 1 is a top front perspective view of a brewing machine and carafe showing our new design;

FIG. 2 is a right side view thereof;

FIG. 3 is a left side view thereof;

FIG. 4 is a top view thereof;

FIG. 5 is a front view thereof;

FIG. 6 is a rear view thereof; and,

FIG. 7 is a bottom view thereof.

The broken lines in the drawing depict portions of the brewing machine and carafe that form no part of the claimed design.
